FAUCET HANDLE

Donald W. Doman, Janesville, Wis., assignor to
Kohler Co., Kohler, Wis.

Filed Aug. 20, 1973, Ser. No. 389,562

Term of patent 14 years

Int. Cl. D23—01

U.S. Cl. D23—29

Fig. 1

Fig. 2

Fig. 3

Fig. 4

Fig. 5

FIG. 1 is a perspective view of a faucet handle showing my new design;

FIG. 2 is a front elevational view thereof;

FIG. 3 is a left-side elevational view thereof;

FIG. 4 is a right-side elevational view thereof; and
FIG. 5 is a top plan view thereof.

I claim:

The ornamental design for a faucet handle, substantially as shown.
